UNITED STATES PATENT OFFICE.

WILLIAM A. ERNER, OF DUBUQUE, IOWA.

SIGNALING WINDOW.

Application filed September 23, 1922. Serial No. 590,152.

To all whom it may concern:

Be it known that I, WILLIAM A. ERNER, a citizen of the United States, residing at Dubuque, in the county of Dubuque and State of Iowa, have invented new and useful Improvements in Signaling Windows, of which the following is a specification.

This invention relates to motor operated vehicles and has particular application to sedans and other closed cars.

In machines of this character, it is often times difficult for the driver to project his arm from the side of the vehicle in order to signal others the direction in which he is about to pursue or when he is about to stop his machine, this being especially true in cold or inclement weather when the adjacent window is entirely closed or substantially so, it being a practice to leave the window slightly open so that the arm of the driver can be projected as stated.

It is therefore the object of the present invention to provide a window construction for vehicles of the above mentioned character including a lower pivot section which may be moved outwardly when it is desired to project the hand at the side of the vehicle for the purpose stated, means being provided for returning the said section to normal position, and holding it fixed with relation to the window frame when closed to prevent rattling.

The nature and advantages of the invention will be better understood when the following detailed description is read in connection with the accompanying drawing, the invention residing in the construction, combination, and arrangement of parts as claimed.

40 In the drawing forming part of this application, like numerals of reference indicate similar parts in the several views, and wherein:—

Figure 1 is a front elevation of the window construction forming the subject matter of the present invention.

Figure 2 is an edge elevation, showing the pivoted section extended.

Figure 3 is a sectional view taken on line 3—3 of Figure 1.

Figure 4 is a sectional view taken on line 4—4 of Figure 1.

Referring to the drawing in detail, 10 represents the portion of a vehicle body, or in other words, the window frame thereof, and this is made in two sections represented

at 10 and 11. The upper section 10 is comparatively large with regard to the lower section 11, the latter being of a size to sufficiently allow the arm of the driver of the vehicle to project his arm through the window opening for the purpose of signaling the drivers of other vehicles as above stated. For this purpose, the lower section 11 is hinged as at 12 and is adapted to swing outwardly to the position illustrated in Figure 2. A cord or any other suitable element indicated at 13 may be utilized for returning the lower section 11 to normal position, this element being arranged with in the body of the car within convenient reach of the driver. The lower section 11 is provided with recesses 14, to accommodate spring pressed ball-like members 15 utilized to hold the section 11 fixed with relation to the section 10 when in closed position, and also serve to prevent rattling of the lower section under all circumstances. Arranged at each side of the section 11 are resilient elements 19 which are curved outwardly and downwardly and designed to be engaged by the lower section as the latter is swung outwardly, and thereby provides a cushioning means to break the fall of the section 11.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

1. In combination, a window supporting frame, a glass including a fixed upper section and a movable lower section, said frame being hinged along its lower edge whereby said section is adapted to be swung outwardly and downwardly to a horizontal position, means for normally holding the lower section in a vertical position, and resilient means projecting outwardly from the main frame and designed to limit and cushion the fall of the lower section, when the latter is pushed outwardly.

2. In combination, a window supporting a main frame, a glass including a fixed upper section secured to said frame, and a movable lower section, a frame for said lower section, said second mentioned frame being hinged along its lower edge whereby

said lower section can be pushed outwardly and downwardly to a horizontal position, means for holding the lower section fixed with relation to the main frame when in a vertical position, and resilient arms projecting outwardly from the main frame and terminating in a plane occupied by said

hinges, the lower ends of said arms being curved inwardly to limit and cushion the fall of the lower section of the glass when 10 the latter is pushed outwardly.

In testimony whereof I affix my signature.

WILLIAM A. ERNER.
